UNITED STATES PATENT OFFICE.

THOMAS E. BAILEY, OF CHICAGO, ILLINOIS.

FOLDING MARKET BAG.

Application filed February 16, 1922. Serial No. 537,103.

To all whom it may concern:

Be it known that I, THOMAS E. BAILEY, a citizen of the United States, residing at Chicago, in the county of Cook and State 5 of Illinois, have invented certain new and useful Improvements in Folding Market Bags, of which the following is a specification.

This invention relates to a parcel carrier 10 which may be collapsed or folded to occupy less space and to be less bulky and cumbersome than when it is unfolded and extended for carrying or containing a quantity of parcels. The principal object of the invention 15 is therefore to so construct and proportion a bag of this kind that it may be readily folded and unfolded; a further object is to provide an article of this description which is pleasing in appearance both folded and 20 unfolded, and which is simple in construction and inexpensive.

In the accompanying drawings, Fig. 1 is a side view of a bag of this kind in folded condition; Fig. 2 illustrates the extended 25 position of the bag on a reduced scale; Fig. 3 is a view of the bag when folded, on the side opposite to that shown in Fig. 1; and Fig. 4 is a sectional view of the bag in a partially folded condition.

An empty market basket takes up substantially the same space and is just about as cumbersome, if not quite so heavy, as a full market basket. The present invention overcomes this objection by providing a bag 30 constructed of canvas, leather, imitation leather, or any other suitable fabric or material, in which the receptacle formed by the fabric can be folded or collapsed and held in the latter position so that it will 35 present a smaller and neater appearance, but can be readily extended for filling or using it whenever desired.

This invention comprises a main receptacle 5 formed of flexible material such as canvas, imitation leather or the like, and the lower portion of the receptacle is substantially rectangular in form. The upper portion has its corners 6 inclined inwardly and connected together at the top so that the 40 top is of less extent and presents a smaller opening than the main body of the bag or receptacle. Around the reduced top of the bag is a binding strip 7 which is sewed or otherwise secured in place and acts as a 45 strengthener or reenforcing strip for the bag.

Extending entirely around the bag from the top to the bottom are two parallel reinforcing strips 8 each intermediate the center and one side of the bag, and these strips 50 extend below the binding strip 7 and are extended upwardly beyond it forming a pair of looped handles 9 by which the bag may be carried. As the strips 8 extend over the bottom of the bag they not only materially re-enforce it but directly support the weight which is carried by the handles 9.

At one side of the bag and between the strips 8 is a pocket 10 with bellows sides allowing it to spread outwardly, and with 55 a flap 11 secured under the binding strip 7 and adapted to close the pocket 10, co-operating devices 12, like a glove fastener, being provided for holding the pocket closed.

At one side of the top of the bag is a 60 narrow strap 13 which is adapted to extend over the opposite edge of the bag, and this strap carries a fastener part 14 which engages with a corresponding fastener part 55 on the other side of the bag.

In collapsing this bag the side flaps 16 outside of the strip 8 are folded inwardly at an angle, as shown more clearly in the broken outline in Fig. 2. This allows the lower edges of the flaps to clear the fastener 65 part 17 disposed just inside of the strip 8, so that when the lower portion of the bag is folded upwardly about a central fold line, these fastener parts 17 will engage with corresponding fastener parts 18 at the upper 70 edge of the bag. When folded, the lower edge of the bag is of substantially the same width as the upper edge or mouth of the bag so that it makes a very neat appearance, and a pocket 10 at one side of the bag is 75 freely accessible by opening the flap 11 for receiving a purse or other small articles which it is not desired to carry in the bag proper. Of course, in this folded position, small articles may be inserted in the top of 80 the bag as well, without entirely unfolding the bag, but for containing any considerable number of parcels the bag must be unfolded by disengaging the fasteners 17 and 18.

I claim:

1. In a foldable market bag, a pair of fasteners at the lower edge at a distance from the center and outer ends thereof, corresponding fastenings at the upper edge of the bag, and flaps foldable inwardly at the 85 sides at an angle upwardly on the side of and to clear the fasteners at the bottom 90

105

110

whereupon these fasteners will engage freely with the corresponding ones at the top when the bottom of the bag and the folded flaps are folded upwardly, reducing the width and length of the bag.

2. A folding market bag comprising a receptacle, the bottom of which is substantially rectangular in shape and with the upper corners of the bag turned inwardly to form a top of reduced size, a pair of supporting straps disposed between the center and outer ends of the bag, extending along

the sides and under the bottom thereof and terminating above the top in handle loops, co-operating fastening devices at the top 15 and bottom of the bag, the bottom corners of the bag being foldable inwardly and upwardly at an angle to clear the bottom fasteners, and the bottom being foldable upwardly upon the flaps to engage the top 20 and bottom fasteners for holding the bag in folded position, reducing the width and length thereof.

THOMAS E. BAILEY.
